AUTOMATIC DOUBLE SHUTTLE WEFT RE-
PLENISHING LOOM

Whitworth F. Bird, Springfield, and William R. Hewton, Philadelphia, Pa., assignors to Collins & Aikman Corporation, Philadelphia, Pa., a corporation of Delaware

Application August 7, 1936, Serial No. 94,726

37 Claims. (Cl. 139—243)

This invention relates to looms wherein two shuttles are employed and wherein the warps are so manipulated as to form superposed weaving sheds through which the respective shuttles are 5 passed in opposite directions simultaneously, with resultant production at one time, of a double fabric, two separate superposed fabrics, or a double pile fabric which may be cut apart on the loom or after removal from the loom, to produce 10 two separate pile fabrics.

More particularly, our invention has reference to multi-shed looms, with automatic weft replenishing mechanism at one side of the loom, whereby replenishment is effected downwardly 15 from above while the lay is substantially in its forward or beat-up position. Each side of the lay is provided with a shuttle box composed of two superposed shuttle compartments. The shuttles may be made to conform to the shape of the shed which they traverse and the compartments are shaped in a similar manner. Because 20 of the superposed relation of the shuttles in such looms, difficulty has been experienced in effecting bobbin substitutions, notwithstanding picking 25 of the shuttles simultaneously in opposite directions so that the shuttle box at the replenishing side of the loom is occupied by but one shuttle at a time for replenishment. It has been proposed heretofore to effect weft replenishment in 30 multi-shed looms by inserting the new weft supply substantially from one side of the shuttle. This method of replenishment has been found to have many disadvantages, one of which is the 35 difficulty encountered in attempting to effectively control the checking of the shuttles in their respective boxes during weaving.

An object of our invention is to overcome the drawbacks heretofore present in connection with weft replenishment in multi-shed looms, which 40 desideratum we realize in practice as hereinafter more fully disclosed, through provision of a relatively simple and reliable automatic mechanism, whereby the two shuttles are caused to pass simultaneously through the sheds from opposite 45 sides of the loom. The replenishing mechanism is mounted on a fixed portion of the loom in such a manner that a full bobbin may be held in position substantially over the upper compartment of the before-mentioned shuttle box when the lay is 50 in forward position. Said bobbin may be controlled so as to replenish a shuttle in either the upper or the lower compartment.

A further object of our invention is to provide 55 in combination with automatic weft replenishing mechanism, ejector means actuated from the lay

to successively thrust filled bobbins from a gravity feed supply magazine into shuttles and incident thereto displace from the shuttles, bobbins which have been substantially exhausted.

Another object of our invention is to provide 5 in a device of the kind referred to, automatic means operable incident to the transfer of a bobbin to position in a shuttle to place another bobbin in a position preparatory to transfer.

Another object of our invention is to provide 10 in a multi-shed loom, a shuttle box on the replenishing side of the loom which comprises two shuttle compartments, the upper having a yieldable front face or wall and shuttle supporting portion which is actuated at the time the shuttle 15 in the lower compartment is being replenished to allow clearance for a replenishing lever.

Another object of our invention is to provide 20 in a multi-shed loom embodying all the features above mentioned, timing means for governing 25 successive operations of the filling replenishing mechanism and the functioning of a weft severing device.

Further objects and advantages of our invention will be manifest from the detailed description 25 of the attached drawings, wherein

Fig. I is a fragmentary view in side elevation of a portion of a loom conveniently embodying the present improvements.

Fig. II is a front elevation of a loom with the 30 central portion broken out and with certain parts omitted to more clearly show the location and arrangement of the present improvements.

Fig. III is a fragmentary detail view, partly in 35 section and viewed from the rear of loom, showing the timing and transfer mechanism which is mounted on a fixed portion of the loom.

Fig. IV is a top plan view of the weft severing device showing its relation to the boxed shuttle.

Fig. V is a side elevation, partly in section of 40 the mechanism shown in Fig. IV.

Fig. VI is a top plan view of the shuttle box on 45 the replenishing side of the loom and shows the pivoted yielding front of the upper compartment.

Fig. VII is a front elevation of the structure 50 shown in Fig. VI.

Fig. VIII is a detail view, partly in section, of a portion of the transfer initiating mechanism.

Fig. IX is a detail view of a dagger and a portion 55 of its control mechanism.

Fig. X is a detail perspective view of a supporting and advancing cradle for the full bobbins in the supply magazine.

Fig. XI is a detail of a cam lever which operates 55 the hook carriage.

Fig. XII is a sub-assembly view, partly in section, taken on line XII—XII of Fig. III and showing the manner in which the bobbins are held and advanced prior to transfer.

5 Fig. XIII is a similar view taken on line XIII—XIII of Fig. III.

Fig. XIV is a detail of the stop cam lever.

Referring first more particularly to Fig. I of the drawings, a frame 10 has appropriately journaled thereon crank shaft 11 and a lower or main shaft 12, which latter may be driven from any suitable source of power in a known manner. The lay swords 13 are mounted on a sword shaft 14 and oscillate therewith. Sword shaft 14 is journaled in the frame and serves to support a part of the picking mechanism. Intermeshing gears 15 and 16 fixed on the shafts 11 and 12 respectively, actuate the oscillating lay beam 17 through pitmans 18, which are pivotally connected to the 15 swords. Carried on the lay beam 17 is a reed 19 which is supported at its top by a reed cap 20, and the two shuttle boxes generally indicated at 21 and 22. Each shuttle box comprises two compartments, the construction of which will be more 20 fully set forth hereinafter.

In general, the picking mechanism is the same on both sides of the loom; and fixed on the sword shaft 14 are supporting members 23 for the picker sticks 24. Pivot at 25 is a treadle arm 26 carrying a shoe 27 adapted to be engaged with picker rollers 28, which are adjustably mounted (Fig. I) on the double armed supporting member 29. The picker sticks are pivoted on short shafts 30 which are fixed on supporting members 23, and comprise 30 a foot 31 for engagement with treadle 26 and an extension 32 whereto is attached one end of a spring 33 which is fixed at its other end to the loom frame 10 and tends to keep the picker stick in its outward position. Any conventional picker stick check means may be used, but since this forms no part of our invention, it is omitted for the sake of clarity. Spring 34 (Fig. I) fixed to the loom at one end tends to counterbalance the weight of the treadle.

45 Numerals 35 and 35' designate pickers which are built to conform to the shape of a cross-section of the shuttle boxes 21 and 22, and the picker stick extends upwardly through registering slots in the lay beam 17, the two shuttle compartments 50 and the pickers.

Each shuttle box is mounted on the movable lay, and, as heretofore set forth, includes two shuttle compartments, one above the other, in which the shuttles 36 and 37 are boxed and held after passing through the sheds formed by the warp threads. The left-hand shuttle box 21 is of ordinary construction, but the right-hand shuttle box 22 is specially constructed in accordance with our invention, see Figs. IV—VII. Shuttle box 22 is 55 on the replenishing side of the loom, and each of its compartments has a longitudinal slot aligned with an opening in the lay beam through which the exhausted or substantially exhausted bobbins are ejected at the time of replenishment. The rear side 38 of the shuttle box 22 comprises a fixed wall of wood or the like. This rear wall is slotted so that swell 39 pivoted on pin 40 is positioned thereon to operate protector mechanism, check the shuttles and the like, all in a known manner. 60 The front of the upper box compartment is divided into two parts 41 and 42, the part 41 being pivoted at the outer extremity of the lay. The part 42 is fixed and its inner extremity is flared to guide the shuttle into the compartment. We 65 prefer to divide the front wall of the upper shuttle

compartment into two parts rather than to reduce the height of a single solid wall at that portion over which the bobbin passes during the transfer operation of the lower shuttle. The front wall of the lower compartment comprises a metal angle 43, adjustably fixed by bolts 44 to the lay beam 17. The top of the lower compartment and the bottom of the upper compartment are one and the same and consists of a plate 45 secured by means of bolts 46 to the rear wall of the shuttle box. This plate, along with pivoted plate 47, forms the bottom of the upper shuttle compartment. The plate 47 pivots about a pin 48 which passes through the bifurcated extension 49 of plate 45. Secured to plate 47 by welding or by 10 any convenient means, such as a bracket or clip 50, is a portion of the front wall of the upper compartment. This wall is substantially co-extensive with plate 47. Inwardly and fixed to the lay beam is a bracket 51 which serves as a support 15 for the fixed portion of the bottom and front of the upper compartment. Clips 52, similar to those above set forth, may connect the bottom and side wall portions. The front walls of both compartments have longitudinal slots which are protected by metal cam plates 53 attached by screws 54 as clearly shown in Fig. VII. The bracket 55 is bent at its top so as to serve as a rest on which the pivoted portion may slide. A cooperating bracket 47' is fixed to the pivoted portion and extends downwardly. The bracket 55 and adjusting screw 57 carried by bracket 47' constitute a fixed stop to limit the rearward movement of the yielding portion of the upper shuttle box compartment. Rearwardly, as used herein, is defined as rearwardly of the loom. This stop arrangement and the springs 64 firmly hold the pivoted portion 41 in proper alignment with the shuttles for normal weaving. The replenishing lever operating as it does to two predetermined fixed extents is adapted to cooperate with movable shuttle compartments which are alternately or successively translated by operation from any convenient moving part of the loom to position two normally superposed shuttles for bobbin replenishment.

45 Master bracket 58 is secured to the forward wall of the lay beam 17 by screws 59. Ears 60 extend outwardly from the bracket to serve as a pivot bearing for the spring-controlled bell crank lever 61, (Fig. I). A roller 62 is pivotally supported 50 between bifurcated end portions of arm 63. Extending at substantially right angles to arm 63 is another arm, the upper end of which passes through a perforation or hole in the yielding portion of the bottom of the upper compartment, 55 (Figs. VI and VII). A pair of springs 64 connect laterally extending ears 65 on the bell crank lever 61 with pins 66 which are fixed to the lay beam 17. These springs are of substantial strength and hold the pivoted member 41 firmly in 60 normal weaving position as determined by the adjustable screw 57. This arrangement causes the front wall to function during weaving in the same manner as if it were fixed but allows it to be displaced when the shuttle in the lower compartment is being refilled. Bracket 58 also carries the V-cut studs 200 and 201 which engage with a dagger hereinafter more fully set forth to effect movement of the replenishing lever or member. The studs 200, 201 are adjustably fixed and of 65 different lengths so that they move the replenishing lever through the proper arc to refill either the upper or lower shuttle.

70 The replenishing magazine 67 hereinbefore mentioned is mounted on a fixed part of the loom

such as the knife rail 68 of a double plush loom. The magazine proper 67 consists of two vertical channel members 69 and 70 which turn rearwardly of the loom at their lower ends and function as a guide for the full bobbins 71 as the latter move into position preparatory to transfer into exhausted shuttles. The lower end of the channel 70, (Fig. III), has a laterally, rearwardly and upwardly extending bearing bracket 72 through which the spring-controlled short shaft 73 is slidable. A stop 74 cooperates with the spring 75 which presses against the side 76 of the bearing bracket 72, thus producing a safety or yielding connection. Fixed by means of a pin 77 to the short shaft 73 is a bobbin clip supporting element 78 having a collar 79 which surrounds said shaft and which is recessed as at 80 to form a relatively firm connection between the offset member of the channel and itself. Substantially opposite the lower end of the channel bar (Figs. XII and XIII), and on this member are pivoted two bobbin retaining elements 81, 82 which cooperate with similar elements 83, 84 on the channels to hold the bobbin in position preparatory to transfer. These bobbin retaining elements are all pressed as by tension springs 85, 86, 87, 88 which tend to hold the members in position to retain a bobbin. Stop screws 89 (Figs. XII and XIII) limit the movement of the elements 81, 82 by the springs 85, 86. The springs 87, 88 act against extensions on pivoted bell crank supports 83, 84. The cradle 90 is supported underneath the channel member by brackets 91, 92; and a yielding latch 93 cooperates with the two notches in the disc 94 to definitely position the cradle.

A device 95 which forms no part of the present invention may be mounted on the extreme end of the knife rail 68 to tension and prevent entanglement of ends 196 of the threads extending from the full bobbins 71 in the magazine 67, and to effect tension on the first pick after replenishment.

Bearings 96, 97 extend from the magazine, and along with the bearing 98, are fixed to the knife rail 68 to support a shaft 99. Mounted loosely on the shaft 99 is a replenishing lever or member 100, of which the end or hammer portion 101 forces a new bobbin into an exhausted shuttle and expels the old bobbin. More specifically, this replenishing lever 100 comprises a yield-head or hammer 101 which is controlled by a compression spring 102 for releasably holding the head to the bobbin element support to prevent damage in the event of improper operation or jamming of the transferring mechanism. Fixed on the shaft 99 is a three-armed lever 103, two arms of which extend above the shaft and between which a spring is mounted to cooperate with an offset ear 104 on the loosely mounted replenishing lever proper 100 to effect a yielding connection. A clock-like spring 105, Fig. III, has one end fixed to the knife rail 68, and the other end to a collar 106 which in turn is fixed to the shaft 99. The purpose of this arrangement is to keep the replenishing lever in retracted position against the knife rail 68, as a stop during normal weaving. A stop screw 107 limits the downward movement of the three-armed lever 103, and hence of the replenishing lever. To avoid overthrow of the replenishing lever on its short stroke, a stop cam lever 108 is pivoted on an ear 109 extending laterally of the three-armed lever 103, (Figs. IX and XIV). This stop cam lever 108 has a projection 110 which rides on the counterweight por-

tion 185 of the dagger 144. When the tip of the dagger is lowered, the stop cam lever 108 is lifted and its end 110 is raised to a position higher than the end of cam 187 on the bracket supporting stop screw 107. The forward movement of the three-armed lever 103 and dagger 144, when they are moved by the V-stud 200 on the lay, causes the abutment 189 on the stop cam lever 108 to align itself with the stop screw 107, and to provide a rigid stop. Fixed on the end of the shaft 99, and on the outside of both bearings is a lever 108 comprising a collar and an arm having two special bifurcated constructed end. This end is specially designed to cooperate with the cradle 90 (Fig. X) which successively positions the bobbins in the magazine channels so that they may be inserted substantially vertically into the exhausted shuttles. The cradle proper comprises a shaft 109 having two supporting members 110 for the bobbin directly above the bobbin in transfer position. On the end of the shaft 109 there is fixed a sector 94 (Fig. XIII) having circumferentially-spaced indentations, and an arm 111 which cooperates with the bifurcated arm 108, on the replenishing lever shaft 99. The indentations cooperate with the beforementioned spring controlled yielding latch 93 to hold the bobbin support 110 either in upright position or in position which allows advancement of the bobbin in the magazine because of the contour of the supporting members. The bifurcated lever 108, being fixed to the shaft 99, is moved a greater or less extent depending on which shuttle is to be refilled. When the replenishing lever 100 gets its long or short stroke to refill an exhausted shuttle, the prong 112 moves completely past the arm 111, and accordingly moves it and the cradle 90 to the same extent regardless of whether or not a shuttle in the upper or lower box is being refilled. The prong 113 on its return stroke resets the magazine cradle and allows it to support a new bobbin which has been advanced by gravity. The supporting members 110 of the cradle 90 are so proportioned in respect to the size of the bobbin heads that the entire supply is not forced backwardly during the resetting action, the bobbin being supported by the members 110 before the first bobbin of the group is forwarded to the lower end of the magazine 67.

To the outer end of the weft replenishing lever 100 shaft 99 (Fig. IV) is affixed an arm 114 having a stud 115 at its upper end capable of turning in the flattened and bored end of a link 116. Small collars 117 and 118 are fixed on the link, and the collar 117 serves as a shoulder for a spring 119 which surrounds said link and presses through a semi-ball 120 at its other end against a knife arm 121 pivoted on a pin 122. A stop bracket 123 secured by bolts 124, has an upstanding projection 125 which limits the forward movement of the knife lever 121 to a definite position regardless of whether the replenishing lever is moved to replenish a shuttle in either the upper or the lower compartment.

The knives 126 (Fig. V) are of the shear type and are pivoted about fixed pins 127 on the flat end 128 of the knife lever 121. Compression springs 129 tend to keep the shear blades open and springs 129' tend to keep the cutting surfaces in shearing contact. Forwardly (of the loom) the shear blades 126 have offset extensions 130, and the compression springs 129 are positioned to keep the shears open to the limit allowed by stops 131 until they are closed by the camming action of the flare on plate 53, through which

they are extended to cut the weft of the exhausted bobbin near the shuttle eye at the time of replenishment. The shuttles 36, 37 have slots which align with the slots in plate 53 when the shuttle is properly boxed.

Replenishing lever 100 (Fig. III) carries an intermediate stud 132 on which cam lever 133 is pivotally mounted with the cam portion 134 facing upwardly, and the projection 135 extends through a slot in the knife rail 68. Accordingly, when the replenishing lever 100 is depressed, the cam lever 133 moves with it and engages a roller 136 at one end of a two-armed hook lever 137 which is pivoted on a stud 137' upstanding from the knife rail 68. The motion of lever 137 imparts a straight rearward thrust to hooks 138, 139 which are fixed to a carriage 140 (Fig. III). The arm of the lever 137 opposite to that on which the roller is mounted is forked and engages a stud 141 on the carriage 140. A T-shaped groove in member 142 fixed to the knife rail 68 guides the carriage. The hooks 138, 139 engage the threads at a point between the selvage and the inner ends of the front walls of the shuttle compartments on the replenishing side. A selvage cleaner generally indicated at 143 (Fig. III) removes the end of the weft from the exhausted bobbin and the end from the first pick from the selvage of the woven material. This may be operated from 30 the oscillating lay.

Fig. I shows the replenishing lever shaft 99 in substantially the same horizontal plane as the front of the bottom of the top shuttle box compartment. This has been found to be even more desirable than positioning it above this plane in which position the hammer portion 101 of the replenishing lever 100 would be moving in the same direction, i. e., forwardly during a portion of the replenishing operation.

At the lower end of the three-armed lever 103, which controls the replenishing lever 100, there is mounted (Fig. IX) a counter-weighted and spring-controlled dagger 144. On said dagger, and extending laterally thereof, are studs 145, 146 which support rollers 147, 148. The spring control comprises a bracket 149 fixed to the under surface of the knife rail. A central vertical portion of the bracket has a pair of offset ears at each side thereof cooperating with rod-like elements 150, 151 around which compression springs 152 are mounted. Rod 150 is bent at the top, and tends to prevent the dagger 144 from moving upwardly, whereas rod 151 supports the dagger and tends to prevent it from moving downwardly, thus establishing effective contact during replenishment. The dagger arm 144 is thus held in neutral position intermediate the V-cut studs 200 and 201 when the lay is forward during normal weaving.

The dagger 144 is moved at the time of substantial exhaustion of the weft bobbin to effect replenishment. Stop cam lever 153 is freely pivoted on a pin 153' in bracket 154 which is secured to the under side of the knife rail 68. The movement of cam lever 153 is limited by the base of the bracket and by the adjustable screw 155 (Fig. I). A laterally extending element 156 is fixed on the stop cam lever 153 and projects over dagger 144 for engagement therewith when the lower shuttle is being refilled, the action being that the dagger lifts the cam lever up against stop screw 155 thus allowing roller 62 on the arm 61 to be forced downwardly, as the lay advances, to effect yielding of the front wall of the upper compartment

and provide clearance for the weft replenishing lever head 101.

The timing mechanism proper may be driven from any moving part on or off the loom, but is shown as being driven by means of suitable gears, 5 sprockets and link chain 157 from the take-up mechanism drive 158.

A bracket 159 fixed on the under side of the knife rail extends downwardly and serves as a bearing for short shaft 160 and stud 161 and, together with another bracket 162, as a bearing for the main timing shaft 163 which extends longitudinally of the knife rail 68. Fixed on shaft 163 is a sprocket wheel 164 driven by link chain 157 (Fig. I). Loosely mounted on shaft 163 for 15 sliding movement but keyed against angular movement is a sleeve 165 comprising a flange 166 and projecting ears 167 through which a pin 168 is positioned as a pivot about which the head 169 of the dagger rotor 170 may turn to a limited extent. The shaft 163 makes a complete revolution for every 16 crossings of each shuttle or picks. The distance between rollers 147 and 148 on the dagger represents predetermined and is an odd number of picks when measured by the number 25 of picks it takes the rotor to pass from one to the other. In the present instance the rollers 147, 148 on the dagger 144 are spaced so that they will co-act with the rotor head 169 on the first and fourth pick of the replenishing cycle. The rotor 30 170 and timing chain 178 are initially set to effect replenishment at substantial exhaustion of the first pair of bobbins. No further setting is necessary. The rotor head 169 is capable of yielding in one direction, and is normally held against a stop 35 167' (Fig. VIII) by means of tension spring 171 (Fig. IX) connected at opposite ends to offset ears respectively on the rotor head 169 and the collar 165.

Short shaft 160 as clearly shown in Fig. VIII 40 carries the fixed sprocket 172 and disc 173. Pivotally mounted for horizontal swinging movement on the bearing hub for the shaft 160 (Fig. VIII) is a two-armed lever 174, one arm of which effects sliding of sleeve 165 against the compression of a 45 spring 175 when a roller 176 on an element extending laterally of the other arm of said lever is engaged by projections 177 on the timing chain 178. The timing chain 178 connects sprockets 179 and 180, the former of which is adjustably mounted. The adjustment allows links to be taken out or added, and hence is adaptable to different lengths of measured bobbins. A one-tooth pinion 181 (Fig. I) is affixed to one end of shaft 163 and accordingly advances the disc 173 one tooth and the 55 chain one link for every 16 picks. A spring-pulled lever 192 carries a roller 193 and holds the disc 173 firmly in tooth-meshed position, but allows manual movement if it is desired to set or alter the time of replenishing.

Weft replenishing actuating ears are positioned on the chain 178 at intervals corresponding to the length of weft on a full bobbin.

Operation

Preparatory to weaving on a multi-shed loom with two shuttles carrying bobbins with measured wefts of a known length as herein set forth, the timing chain 178 is placed about sprockets 179 and 180 so that when a set of ears thereon reach 70 the roller 178 to initiate replenishment, the measured bobbins will be substantially exhausted and the rotor head 169 will be positioned ahead of rollers 147 and 148 on the dagger 144. The chain, being advanced every 16 picks, will on 75

a given pick after engaging the roller cause two-armed lever 174 to shift the sleeve 165 and hence the rotor head into line with the rollers on the dagger. Continued weaving will, after one or 5 more picks, cause head 169 to engage roller 147 and lower the dagger point into the path of the V-cut stud 200. The forwardly moving lay will carry the dagger forwardly with it and turn three-armed lever 103 about its shaft 99 against 10 the action of the clock-like spring. This motion of the three-armed lever causes the replenishing lever to descend and engage a full bobbin in the magazine 67, such engagement taking place before the lay is on front dead center. Continued 15 movement of both the lay and the replenishing lever causes the new bobbin to be inserted in the upper shuttle and the exhausted bobbin to be concurrently ejected therefrom. The downward motion of replenishing lever 100 and the con- 20 current rotation of the carriage lever 137 causes the hooks 138, 139 on the carriage to be moved inwardly and the upper hook to engage the weft of the upper shuttle. Simultaneously, shaft 99 and link 116 moves the shears inward where they 25 are cammed to closed position as they enter further into plate 53, and cut the weft from the old bobbin as the lay moves forwardly. The V-stud 200 moves away from the dagger and allows shaft 99 and replenishing lever to be re- 30 turned to their original positions by the clock spring. The hooks are withdrawn, carrying with them the cut end of the exhausted bobbin, and the cutters are returned to their original position. The rearward motion of the lay permits 35 the weft caught on the hook to be completely withdrawn from the shuttle box.

Simultaneously with actuation of the replenishing lever 100, the link 108 moves downwardly and turns the notched sector 94 as clearly shown 40 in Figs. XII and XIII to advance a bobbin in the magazine. The reverse movement of shaft 99 moves sector 94 back to its original position. In the meantime, the exhausted bobbin has passed down through the lay beam free from the loom. 45 On the fourth pick, the rotor head engages roller 148 and moves the dagger up into the path of V-stud 201. The action is similar to that above described except that stud 201 moves the dagger a greater distance to replenish the lower shuttle. Elevation of dagger 144 raises cam lever 153 by means of the laterally extended element 156 on the latter and allows the roller 62 of the bell crank 61 (Fig. I) to pass under and raise 50 said cam lever up against adjustable screw 155. Continued inward motion of the lay causes the bell crank to pivot about its fulcrum and move the yielding portion 41 of the upper shuttle box compartment as the hammer on the replenishing lever moves deep in the shuttle box to replenish 55 the lower shuttle. The V-cut stud 201, projecting as it does ahead of V-cut stud 200, engages the dagger earlier in the lay's forward movement and accordingly moves the replenishing lever a greater distance to project the filled bobbin into 60 the lower shuttle and expel the exhausted bobbin by said projection. There is an actual movement of the bobbin away from the replenishing lever head. The operation of the shears, hooks and the advancement of the bobbins is similar to 65 their first described motions except that this time the lower hook functions 139 to withdraw the cut weft, and the stop 125 has limited the inward motion of the shears. One or more picks later, the one-tooth pinion 181 on the shaft 163 advances the disc 173 and the chain. This, of 70

75 course, occurs before the rotor has again engaged a roller on the dagger. The temple clears the selvage of the cut end of the old bobbin and the end of the first pick of the new bobbin.

Having thus described our invention, we claim: 5

1. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a member movable two predetermined different downward extents to engage a full bobbin in the magazine and project in into a shuttle in either the upper or lower shuttle compartment depending on the extent the member is moved, means for determining the extent of the movement of the member and actuating means for said member and determining means. 10 15 20

2. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a member movable two predetermined different downward extents to engage a full bobbin in the magazine and project it into a shuttle in either the upper or lower shuttle compartment depending on the extent the member is moved, means for determining the extent of the movement of the member, means for returning the member to its original position and actuating means for said member and determining means. 25 30 35 40 45

3. In a multi-shed loom, the combination of a movable lay, picking mechanism on both sides of the lay, a shuttle box mounted on one side of the movable lay having superposed upper and lower shuttle compartments, said lay and compartments having a continuous opening sufficiently large for a shuttle bobbin to pass through, a magazine for filled bobbins having a separate support for a single bobbin, a weft replenishing mechanism comprising a member movable two predetermined different downward extents to engage the full bobbin on the separate support to project it into a shuttle in either the upper or the lower compartment depending on the extent the member is moved, means for determining the extent of movement of the member and actuating means for said member and determining means. 50 55 60 65

4. In a multi-shed loom, the combination of a movable lay, picking mechanism on both sides of the lay, a shuttle box mounted on one side of the movable lay having superposed upper and lower shuttle compartments, said lay and compartments having a continuous opening sufficiently large for a shuttle bobbin to pass through, a magazine for filled bobbins having a separate support for a single bobbin, a filled bobbin on said separate support; a weft replenishing mechanism comprising a member movable two predetermined different downward extents to engage the full bobbin on the separate support to 70 75

project it into a shuttle in either the upper or the lower shuttle compartment depending on the extent the member is moved, means for determining the extent of movement of the member, actuating means for said member and determining means, and means for returning the member to its original position.

5. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a pivoted member movable two predetermined different downward extents to engage a full bobbin in the magazine and project it into a shuttle in either the upper or lower shuttle compartment depending on the extent the member is moved, means for determining the extent of the movement of the member and actuating means for said member and determining means.

6. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a pivoted member movable two predetermined different downward extents to engage a full bobbin in the magazine and project it into a shuttle in either the upper or lower shuttle compartment depending on the extent the member is moved, means for determining the extent of the movement of the member, actuating means for said member and determining means, and means for returning the member to its original position.

7. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising member pivoted on a stationary loom part movable two predetermined different downward extents to engage a full bobbin in the magazine and project it into a shuttle in either the upper or lower shuttle compartment depending on the extent the member is moved, means for determining the extent of the movement of the member and actuating means for said member and determining means.

8. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenish-

ing mechanism comprising a member pivoted on a stationary loom part movable two predetermined different downward extents to engage a full bobbin in the magazine and project it into a shuttle in either the upper or lower shuttle compartment depending on the extent the member is moved, means for determining the extent of the movement of the member, actuating means for said member and determining means, and means for returning the member to its original position.

9. In a multi-shed loom, a combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a member movable two predetermined different downward extents to engage a shuttle bobbin in the magazine and to project it into a shuttle in either the upper or lower shuttle compartment depending on the extent the member is moved, means for determining the extent of movement of the member, weft withdrawing means operated by the member, and actuating means for said member.

10. In a multi-shed loom, a combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a member movable two predetermined different downward extents to engage a shuttle bobbin in the magazine and to project it into a shuttle in either the upper or lower compartment depending on the extent the member is moved, means for determining the extent of movement of the member, cutting means operatively connected to said member and movable the same amount to sever the weft of the box shuttle when the member is moved sufficiently to effect refilling of the shuttle in either the upper or lower compartment, actuating means for said member, cutting means and determining means.

11. In a multi-shed loom, a combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, a magazine for filled bobbins, a weft replenishing mechanism comprising a member movable two predetermined different downward extents to engage a shuttle bobbin in the magazine and to project it into a shuttle in either the upper or lower shuttle compartment depending on the extent the member is moved, means for determining the extent of movement of the member, cutting means operatively connected to said member and movable the same amount to sever the left of the boxed shuttle when the member is moved sufficiently to effect refilling of the shuttle

in either the upper or lower compartment, a stop for said cutting means, actuating means for said member, cutting means and determining means, and means for returning the member and cutting means to their original positions.

5 12. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass 10 through, a yieldable portion on said upper compartment, a magazine for filled bobbins, a weft replenishing mechanism comprising a member movable two predetermined different downward extents to engage a full bobbin in the magazine 15 and to project it into a shuttle in either the upper or lower shuttle compartment depending on the extent the member is moved, means for determining the extent of movement of the member, means for moving the yieldable portion on said 20 upper compartment when the member is moved to refill the shuttle in the lower compartment and actuating means for said member and determining means.

25 13. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper 30 and lower shuttle compartments, said lay and compartments having a continuous opening sufficiently large for a shuttle bobbin to pass through, a yieldable portion controlled by the determining means on said upper compartment, a magazine 35 for filled bobbins, a weft replenishing mechanism comprising a member movable two predetermined different downward extents to engage a full bobbin in the magazine and to project it into a shuttle in either the upper or lower shuttle compartment depending on the extent the member is moved, means for determining the extent of movement of the member, means for moving the yieldable portion on said upper compartment when the member is moved to refill the shuttle in the lower compartment and actuating means 40 for said member and determining means.

45 14. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening 50 sufficiently large for shuttle bobbin to pass through, a yieldable front portion on said upper compartment, a magazine for filled bobbins, a weft replenishing mechanism comprising a member movable two predetermined different downward extents to engage a full bobbin in the magazine and to project it into a shuttle in either the upper or lower shuttle compartment depending on the extent the member is moved, means for determining the extent of movement of the member, means for moving the yieldable portion on said upper compartment when the member is moved to refill the shuttle in the lower compartment and actuating means for said member and determining means.

55 15. In a multi-shed loom, the combination of

a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through, swells in the rear of both shuttle compartments, a yieldable front portion on said upper compartment, a magazine for filled bobbins, a weft replenishing mechanism comprising a member movable two predetermined different downward extents to engage a full bobbin in the magazine and to project it into a shuttle in either the upper or lower shuttle compartment depending on the extent the member is moved, means for determining the extent of movement of the member, means for moving the yieldable portion on said upper compartment when the member is moved to refill the shuttle in the lower compartment and actuating means for said member and determining means.

16. In a multi-shed loom having a movable lay, picking mechanism on both sides of the lay, a pair of bobbin carrying shuttles adapted to be simultaneously picked from opposite sides of the lay, a shuttle box mounted on one side of the movable lay having superposed upper and lower compartments; a magazine for filled bobbins, a weft replenishing mechanism comprising a member movable two predetermined different downward extents into the upper and lower shuttle compartments respectively, means for determining the extent the member is moved, comprising a pivoted dagger having a pair of elements laterally of said dagger but on opposite sides of the pivot point to move the dagger upwardly and downwardly to position the dagger means on the lay to engage the dagger when it is so positioned to move it and the member to one of the fixed extents.

17. In a multi-shed loom having a movable lay, picking mechanism on both sides of the lay, a pair of bobbin carrying shuttles adapted to be simultaneously picked from opposite sides of the lay, a shuttle box mounted on one side of the movable lay having superposed upper and lower compartments, a magazine for filled bobbins, a weft replenishing mechanism comprising a member movable two predetermined different downward extents into the upper and lower shuttle compartments respectively, means for determining the extent the member is moved, comprising a pivoted dagger having a pair of elements laterally of said dagger but on opposite sides of the pivot point so that the dagger may be moved upwardly and downwardly to position the dagger, means on the lay to engage the dagger when it is so positioned to move it and the member to one of the fixed extents as the lay moves forwardly, timing means comprising a refilling initiating means which advances after a plurality of picks and a continuous driving means for said timing means.

18. In a multi-shed loom, the combination of a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, said lay and compartments having a continuous opening sufficiently large for a shuttle bobbin to pass through; a magazine for filled bobbins, weft replenishing

mechanism comprising a member movable two predetermined downward extents to engage a shuttle in the magazine and to project it into either the upper or the lower shuttle box depending on the extent the member is moved; resiliently mounted cutting means operatively connected to the member and movable the same amount for either movement of the member, a stop for said cutting means, means for determining the extent of movement of the member and actuating means for said member, cutting means and determining means.

19. In a multi-shed loom, having a movable lay, picking mechanism on both sides of the loom, a pair of bobbin carrying shuttles adapted to be simultaneously picked from opposite sides of the lay, a shuttle box mounted on one side of the movable lay having superposed upper and lower compartments, a weft replenishing mechanism comprising a member movable two predetermined different downward extents respectively into the upper and lower shuttle compartments, a resiliently mounted cutting means operatively connected to the member and movable the same amount on either movement of the member, a stop for said cutting means, means for predetermineding the extent the member is moved, comprising a pivoted dagger having a pair of elements laterally of said dagger but on opposite sides of the pivot point so that the dagger may be moved upwardly and downwardly to position the dagger, means to engage the dagger when it is so positioned to move it and the member to one of the fixed extents as the lay moves forwardly, timing means comprising a replenishing initiating means which advances after a plurality of picks, means coordinating the timing means with the dagger, a continuous driving means for said timing means, and means for yieldingly holding the initiating means in position while it is at rest.

20. In a multi-shed loom, having a movable lay, picking mechanism on both sides of the loom,

a pair of bobbin carrying shuttles adapted to be simultaneously picked from opposite sides of the lay, a shuttle box mounted on one side of the movable lay having superposed upper and lower compartments, a weft replenishing mechanism comprising a member movable two predetermined different downward extents respectively into the upper and lower shuttle compartments, a resiliently mounted cutting means operatively connected to the member and movable the same amount on either movement of the member, a stop for said cutting means, means for determining the extent the member is moved, comprising a pivoted dagger having a pair of elements laterally of said dagger but on opposite sides of the pivot point so that the dagger may be moved upwardly and downwardly to position the dagger, means to engage the dagger when it is so positioned to move it and the member to one of the fixed extents as the lay moves forwardly, timing means comprising a replenishing initiating means, a sleeve with a head and a shaft, said sleeve being movable on the shaft under control of the timing means to position the head in alignment with the elements on the dagger at predetermined times.

21. In a multi-shed loom having a movable lay, picking mechanism on both sides of the loom, a pair of bobbin carrying shuttles adapted to be simultaneously picked from opposite sides of the lay, a shuttle mounted on one side of the movable lay having superposed upper and lower shuttle compartments, weft replenishing mechanism comprising a member movable two predetermined different downward extents respectively into the

upper and lower shuttle compartments, a resiliently mounted cutting means operatively connected to the member and movable the same amount on either movement of the member, a stop for said cutting means, means for determining the extent the member is moved, comprising a pivoted dagger having a pair of elements laterally of said dagger but on opposite sides of the pivot point so that the dagger may be moved upwardly and downwardly to position the dagger, means to engage the dagger when it is so positioned to move it and the member to one of the fixed extents as the lay moves forwardly, timing means comprising a replenishing initiating means which advances after a plurality of picks, means coordinating the timing means with the dagger, a continuous driving means for said timing means, and means for yieldingly holding the initiating means in position while it is at rest.

22. In a multi-shed loom, a movable lay, picking mechanism on both sides of the lay, a pair of bobbin carrying shuttles adapted to be simultaneously picked by the picking mechanism from opposite sides of the lay, a shuttle box mounted on one side of the movable lay having superposed upper and lower shuttle compartments, a magazine for filled bobbins, said magazine comprising a yielding support for a single bobbin, and a cradle to support the remaining bobbins in a magazine and to permit one of said bobbins to advance to the support, a member movable two predetermined different downward extents into respectively the upper and lower shuttle compartments when the lay is substantially in forward position, stops for said member, means for predetermineding the extent of movement of said member and additional means operated by the member to move the cradle the same extent when either the upper or lower shuttle is being replenished.

23. In a multi-shed loom, a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, a magazine for filled bobbins, said magazine comprising a support for a single bobbin and a cradle to support the remaining bobbins and to permit one of said bobbins to advance to the support, a member movable two predetermined different downward extents respectively into the upper and lower shuttle compartments when the lay is substantially in forward position, stops for said member, resiliently mounted cutting means positively connected to the member and movable the same amount on either movement of the member, a stop for said cutting means, means for predetermineding the movement of said member and additional means positively connected to the member to move the cradle the same extent when either the upper or lower shuttle is being replenished, means to withdraw said member from either shuttle compartment and to reset the cradle operating means, cradle and cutting means.

24. In a multi-shed loom, a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, a magazine for filled bob-

bins, said magazine comprising a support for a single bobbin and a cradle to support the remaining bobbins and to permit one of said bobbins to advance to the support, a member movable two predetermined different downward extents respectively into the upper and lower shuttle compartments when the lay is substantially in forward position, stops for said member, resiliently mounted cutting means positively connected to the member and movable the same amount on either movement of the member, a stop for said cutting means, means for predetermined the extent of movement of said member comprising a pivoted dagger having a pair of elements on said dagger but on opposite sides of the pivot point, means to tilt the dagger either upwardly or downwardly to position the dagger, means to engage the dagger when so positioned to move it and the member to one of the fixed extents, whereby the single bobbin is transferred into the shuttle and the bobbin in the shuttle ejected, additional means operatively connected to the member to move the cradle and the cutting means the same amount when either the upper or lower shuttle is being replenished, means to withdraw said member from either shuttle compartment and to reset the dagger, the cradle operating means, the cradle and cutting means.

25. In a multi-shed loom, a movable lay, picking mechanism on both sides of the lay, a pair of bobbin carrying shuttles adapted to be simultaneously picked from opposite sides of the lay, a shuttle box mounted on one side of the movable lay having superposed upper and lower shuttle compartments, a magazine for filled bobbins, said magazine comprising a support for a single bobbin and a cradle to support the remaining bobbins and to permit one of said bobbins to advance to the support, a member movable two predetermined different downward extents respectively into the upper and lower shuttle compartments when the lay is substantially in forward position, stops for said member, resiliently mounted cutting means positively connected to the member and movable the same amount on either movement of the member, a stop for said cutting means, means for predetermined the extent of movement of the said member comprising a pivoted dagger having a pair of elements on said dagger but on opposite sides of the pivot point, means to tilt the dagger upwardly and downwardly to position the dagger, means to engage the dagger when so positioned to move it and the member to one of the fixed extents, whereby the single bobbin is transferred into the shuttle and the bobbin in the shuttle ejected, additional means operatively connected to the member to move the cradle and cutting means the same amount when either the upper or lower shuttle is being replenished, timing means comprising a replenished initiating means, a sleeve and a shaft, said sleeve being movable on the shaft to a position in alignment with the members on the dagger at predetermined times, means for yieldingly holding the initiating means while it is at rest and means to withdraw said member from either shuttle compartment and to reset the dagger, the cradle operating means, the cradle and cutting means.

26. In a multi-shed loom, the combination of a movable lay, picking mechanism at both sides of the lay, a pair of bobbin-carrying shuttles adapted to be simultaneously picked from opposite sides of the lay, a shuttle box mounted on

one side of the movable lay having superposed upper and lower shuttle compartments, said lay and compartments having a continuous opening sufficiently large for a shuttle bobbin to pass through, a magazine for filled bobbins, a filled bobbin in said magazine; a weft replenishing mechanism comprising a member movable two predetermined different extents to engage a full bobbin in the magazine and to move it into a shuttle in either the upper or lower shuttle compartment depending upon the extent the member is moved, a front wall for said upper box having a portion aligned with the full bobbin to guide the shuttle while it is being boxed and being clear of the path of the full bobbin and movable member during refilling of the shuttle in the lower compartment, means for determining the extent of the movement of the member, and actuating means for said member.

27. In a double shuttle loom, a movable lay; a shuttle box with two superposed vertically-aligned shuttle compartments at each side of the loom mounted on the lay; a pair of shuttles; means for concurrently throwing the shuttles across the lay in opposite directions between corresponding compartments of the respective shuttle boxes; a magazine for filled bobbins on one side of the loom; and means movable two different extents relatively to said shuttle compartments to vertically replace bobbins in the respective shuttles with filled bobbins from the magazine at different times while said shuttles respectively rest temporarily in their respective compartments in one of the shuttle boxes; means for selecting in which of either shuttle compartment a shuttle is to be replenished and actuating means for the movable means whereby to transfer a bobbin into a shuttle in the selected compartment.

28. In a loom, a movable lay, a pair of automatic weft replenishing bobbin shuttles; picking mechanism for picking the shuttles oppositely and simultaneously across the lay; a shuttle box mounted at one side of the lay, having a pair of superposed vertically-aligned shuttle compartments and a straight bobbin passage extending therethrough, for boxing the shuttles; a bobbin support; means for engaging a bobbin on the support and transferring it vertically into a shuttle in either compartment of the shuttle box and means for giving said first named means either of two extents of movement and means for governing the extent of movement.

29. In a multiple shed loom, a movable lay, a pair of shuttles; a shuttle box mounted at one side of the lay having an upper and under superposed vertically-aligned shuttle compartment, with a vertical opening extending continuously therethrough; weft replenishing mechanism including a bobbin displacing member for passing it two different extents into the vertical opening of the shuttle box in selectively replenishing exhausted individual shuttles respectively in the respective compartments; means for selecting the time at which both of the shuttles are successively replenished in their respective compartments and actuating means for the movable means whereby to transfer a bobbin into a shuttle in each compartment at different times.

30. In a multiple shed loom, a movable lay, a pair of shuttles; a shuttle box mounted at one side of the lay having a pair of superposed vertically-aligned shuttle compartments with a substantially straight vertical opening extending continuously therethrough; weft replenishing

- mechanism including a bobbin displacing member arranged to be passed into the vertical opening of the shuttle box; and a pivoted actuating element to cause said member to be thrust two different extents into the shuttle box in selectively replenishing exhausted individual shuttles respectively in the respective compartments; means for giving said pivoted actuating element either of the selected extents of movement and 5 means for governing said selection.
31. In a multiple shed loom, a movable lay; a pair of shuttles; a shuttle box mounted at one side of the lay having two superposed vertically-aligned shuttle compartments with a straight 10 vertical opening extending continuously therethrough; weft replenishing mechanism including a lay-actuated member arranged to be passed two different extents into the vertical opening of the shuttle box in selectively replenishing exhausted individual shuttles respectively in the 15 respective compartments; means for giving said member either of the selected extents of movement and means for governing said selection.
32. In a loom, a movable lay, a pair of automatic weft replenishing bobbin shuttles; a shuttle box mounted at one side of the lay, having a pair of superposed vertically-aligned compartments for boxing the shuttles; a bobbin support; means for engaging a bobbin on the support and 20 for transferring it vertically into a shuttle in either of the compartments of the shuttle box; means for giving said first named means either of the selected extents of movement and means for governing said selection.
33. In a loom, a movable lay, a pair of automatic weft replenishing bobbin shuttles; a shuttle box mounted at one side of the lay, having a pair of superposed vertically-aligned compartments for boxing the shuttles; a bobbin support; means for engaging a bobbin on the support and for 25 transferring it vertically into a shuttle in either of the compartments of the shuttle box; means to be selected for predetermining the extent of movement of the said bobbin engaging means; means to select said predetermining means and 30

means for actuating said selected means and the bobbin engaging means.

34. In a double shuttle loom, a movable lay, a shuttle box mounted at one side of the lay, having a pair of superposed vertically-aligned compartments in a continuous vertical bobbin passage therethrough; a bobbin transfer means arranged to pass down through the upper compartment and beyond to an extent sufficient to transfer a bobbin into a shuttle in the lower compartment; 10 means for selecting the time of such passage and actuating means for said bobbin transfer means.

35. In a loom, a movable lay, a pair of automatic weft replenishing shuttles; picking mechanism for picking the shuttles oppositely and simultaneously across the loom; a shuttle box on one side of the lay, having a pair of aligned shuttle compartments and a continuous bobbin passage extending therethrough; a bobbin support; means movable to either of two extents to 15 engage a bobbin on the support and to transfer it into a shuttle in either of the compartments of the shuttle box; means for giving said first named means either of the two extents of movement and means for governing the extent of movement. 20

36. A loom in accordance with claim 28 wherein in the shuttle box has a swell for each compartment on the same side of the shuttle box, a yieldable portion on the upper compartment on the side opposite the swells and means to move said 30 yieldable portion to provide clearance for the transfer means as the lay approaches front center for replenishing a shuttle in the lower compartment. 25

37. In a loom in accordance with claim 28 wherein the shuttle box has swells on the rear of both shuttle compartments, a yieldable portion on the upper compartment on the side opposite the swells; means mounted on a fixed part of the loom to move said yieldable portion to provide 35 clearance for the transfer means as the lay approaches front center for replenishing a shuttle in the lower compartment. 40
